APPARATUS FOR CONTROLLING THE SUPPLY OF FUEL OIL TO A BURNER

Jesse C. Johnson, Oakland, Calif.

Application March 7, 1935, Serial No. 9,769

1 Claim. (Cl. 137—153)

This invention is an apparatus for controlling the supply of fuel oil to a burner.

One of the objects of the invention is to provide simple and efficient means for maintaining a constant volume flow of oil to the burner atomizer, irrespective of the viscosity or temperature of the oil. A further object is to remove from the oil in the suction line, or any other portion of the system, such air as may be entrapped in the oil, and to remove the oil which contains the air to the storage tank.

The invention will be hereinafter fully set forth and particularly pointed out in the claim.

In the accompanying drawings:

Fig. 1 is a diagrammatic view, partly in section illustrating an oil feed control apparatus constructed in accordance with the invention. Fig. 2 is a longitudinal sectional view illustrating the air removing device, the plane of the section being at an angle to the plane of the section illustrated in Fig. 1. Fig. 3 is a transverse sectional view on the line 3—3, Fig. 2. Fig. 4 is a detail view of the handle and quadrant. Figure 5 is a diagrammatic view, partly in section, illustrating a modified form of apparatus.

Referring to the drawings, 10 designates a storage tank, and 11 an oil pump of the type commonly employed on oil burners. Leading from the tank 10 is an outlet pipe 12, which at its delivery end is connected with the pump 11, which is provided with a discharge pipe 13.

In the form of the invention illustrated in Figs. 1, 2 and 3, the pipe 13 discharges into the casing 14, which casing is provided with a chamber 15 having an inlet port 16 and three outlet ports 17, 18 and 19. Located within the chamber 15 is a movable piston 20, which is provided with a flange 21 normally pressed toward a shoulder 22 of the casing by means of a spring 23. The tension of the spring may be regulated by an adjusting screw 24 bearing against the abutment 25, as clearly shown in Figs. 1 and 2. The flange 21 is provided with three slots or openings therein indicated at 26, 27 and 28, respectively, so positioned as to register with the outlets 17, 18 and 19, respectively.

Leading from the outlet 17 is a return pipe 30, which discharges into the tank 10. It will be noted that the slot or orifice 26 is of considerable less area than the cross-sectional area of the conduit 30. The oil feed pipe 29 for the burner leads from the outlet opening 18, and may be connected with the burner in any suitable manner not shown, it being noted however, that the outlet 27 is of such small area that all of the oil

supplied to the chamber 15 by the pump 11 will not pass therethrough. The outlet opening 19 is provided with a by-pass pipe 31, which leads from the chamber 15 to the supply pipe 12 in such manner as to by-pass the pump 11, said pipe 31 joining the pipe 12 between the pump and the tank.

In operation, at the time that current is admitted to the usual burner atomizer motor (not shown), the motor for operating the pump 11 is simultaneously energized. The action of the pump is to draw oil from the tank 10 through the conduit 12 and to deliver it through pipe 13 to the center of the receiving end of the chamber 15, the pressure of the oil serving to move the piston valve 20 against the tension of its spring so as to bring the openings 26, 27 and 28 in registry with the respective outlets 17, 18 and 19. As the piston valve is moved back oil will simultaneously flow through all of the outlets, but the outlet 26 being the highest, any air which may be carried into the chamber 15 with the oil tends to move upwardly through the port 26 into the pipe 30 and will thereby be returned to the tank 10. At the same time, oil will flow through the port 27 into outlet 18 and from thence through pipe 29 to the burner. Inasmuch as the ports thus far described are not of sufficient combined area to carry the entire flow of oil, a part of the oil will also flow out of the port 28 and outlet opening 19 through the by-pass pipe 31 and back to the pump, so that the by-pass pipe provides a means for maintaining a constant supply of oil sufficient to maintain the feed demands of the burner supply pipe 29.

The piston 20 is rotatively mounted within the casing 14 for the purpose of adjusting the volume of flow through the respective outlets. This rotative adjustment may be effected in any desired manner, but preferably by means of an eccentric pin 32 carried by a rotatively mounted shaft 33, provided with a handle 34 located opposite a quadrant 35. It will be observed that by maintaining a continuous and definite quantity of oil from pump 11 through the pipe 13, the piston valve 20 will automatically move against the tension of its spring until the three oil flow ports 26, 27 and 28 open to the proper extent to allow a definite amount of oil to pass under a given pressure setting of the spring. Assuming the ports 26, 27 and 28 to be of equal width, the quantity of fuel passing through the port 27 and through the pipe 29 to the burner atomizer would be one-third of the quantity of oil supplied by pump 11 through pipe 13. The same will be

true of the flow through ports 26 and 28. By 5 rotatively adjusting the piston valve 20 to the position illustrated in Fig. 3, only one-half of the area of port 27 is available, and with the ports 26 and 28 being of equal area, there would be one-fifth of the oil furnished by the pump 11 passing through the chamber into the pipe 29.

It has been previously pointed out that by 10 reason of the oil flow port 28, a portion of the oil furnished by the pump will pass through the pipe 31 and to the suction side of the pump through the T 36, and this considerable portion of the oil from which the air has been removed will furnish a part of the oil drawn by the pump. 15 Thus, after the pump has been put into operation, only a portion of the oil required by the pump is drawn from the tank 11. In this manner, there is always sufficient oil to enable the pump to pass a constant volume through the 20 pipe 13 to chamber 15. Having a constant quantity of oil delivered to said chamber, the piston valve 20 will automatically compress the spring 23 and allow all of the oil furnished by the pump to distribute itself through the ports 26, 27 and 25 28 in accordance with the rotative setting of the piston valve. As the viscosity of the oil changes, the piston valve will automatically move to a point that will open the flow ports 26, 27 and 28 to the proper extent.

30 In the form illustrated in Fig. 5, in lieu of the casing 14 and the viscosity valve 20, the pipe 13 discharges into the casing 14^a of an air separating device. Said casing is provided with an internal chamber having therein a cylindrical screen 15^a 35 surrounding a branch 16^a of the outlet pipe, which branch extends downwardly into the casing 14^a a substantial distance through the top thereof. It will be noted that the conduit 13 communicates with the bottom of said casing and that the 40 return pipe 30 leads from the top of the casing 14^a. It will also be observed that the last-mentioned conduit communicates with the casing 14^a through a coupling 37, which is provided with an orifice 38 of considerably less diameter than the diameter of the conduit. The outlet pipe 16^a is connected with an oil feed pipe 39 of reduced diameter, which constitutes the oil feed to the burner atomizer. The pipes 16^a and 39 are connected by a T 40, which is provided with a 45 transverse wall 41 having a small orifice 42 of less diameter than the diameter of either of the pipes 16^a or 39.

50 The by-pass pipe 31^a leads from the T 40 to the T 43. It will be noted that the last-mentioned T is provided with an orifice 44 of less diameter than the diameter of the conduit 12, or of the by-pass pipe 31^a.

In operation, the action of the pump is to de-

liver the oil to the casing 14^a through the bottom thereof. The passage of any oil through the screen 15^a results in the elimination of air bubbles therefrom, and the oil from which the air has been removed passes out of the chamber through the pipe 16^a, a portion of the oil also passing out into the conduit 30 and back to the tank, the stream of oil passing out through the conduit 30 carrying with it such air as has been separated from the oil, which passes 10 through the screen 15^a. The by-pass pipe 31^a acts in the same manner as the by-pass pipe 31 illustrated in Fig. 1.

The advantages of the invention will be readily 15 understood by those skilled in the art to which it belongs. It will be particularly noted that by means of either form of the invention as described, a constant volume oil flow to the burner atomizer is maintained, irrespective of the viscosity or the temperature of the oil. A further 20 important advantage is that the air is efficiently separated from the oil in the suction line in such manner as to prevent it from being delivered to the burner atomizer, and the trapped air is conducted out of the stream and delivered into the 25 storage tank.

Having thus explained the nature of the invention and described an operative manner of constructing and using the same, although without attempting to set forth all of the forms in 30 which it may be made, or all of the forms of its use, what is claimed is:

Apparatus for controlling the flow of fuel oil to a burner comprising a casing having a central bore therein, an inlet opening at one end of said bore through which fuel oil under pressure may be admitted to said bore and a plurality of outlet openings spaced about the periphery of said bore through which said fuel oil may be discharged from said bore, a piston, slideable under 40 the influence of the pressure of the fuel oil entering said inlet opening axially of said bore, having portions thereof covering and normally closing said outlet openings and provided with slots registerable with said outlet openings when said 45 piston is moved to gradually uncover said openings, said piston having a recess in the periphery thereof, resilient means for resisting the movement of said piston axially of said bore, a shaft journaled in said casing, said shaft having secured at one end thereof a pin axially offset with respect to the shaft axis and engaged in the recess of said piston, and means for rotating said shaft to move said pin in an orbital path about said shaft axis and impart rotary motion to said 50 piston.

JESSE C. JOHNSON.
